U.S. Appl. No. 29/383,346, filed Jan. 14, 2011, Widalys Desoto-Burt.

Primary Examiner — Susan Bennett Hattan

(74) Attorney, Agent, or Firm — Linda M. Sivik

(57) **CLAIM**

The ornamental design for a closure, as shown and described.

DESCRIPTION

FIG. 1 is a perspective view of a closure, embodying our new design;

FIG. 2 is a first side elevational view of the closure of FIG. 1; FIG. 3 is a second side elevational view of the closure of FIG. 1;

FIG. 4 is a front elevational view of the closure of FIG. 1; FIG. 5 is a back elevational view of the closure of FIG. 1; FIG. 6 is a bottom plan view of the closure of FIG. 1; and, FIG. 7 is a top view of the closure of FIG. 1.

The broken lines shown in the drawings are for illustrative purposes only and form no part of the claimed design.

1 Claim, 2 Drawing Sheets
